CHAIR WITH FLEXIBLE SEAT

Rolo D. Hill, Los Angeles, Calif.

Application July 10, 1945, Serial No. 604,178

3 Claims. (Cl. 155—187)

1

This invention relates to improvements in chairs.

One object of the present invention is to provide an improved chair of the collapsible type wherein the chair is composed of a pair of spaced side members to the lower ends of which are secured the lower ends of an X-brace construction, the X-brace carrying seat rails adjacent its upper end enabling a seat to be suspended therebetween. The X-brace construction being made up of pivotally connected legs or elements enables the side members to be moved towards each other. This general type of collapsible chair is well known in the art but most chairs embodying a pivoted X-brace construction to enable collapse of the side members towards each other have been built heretofore on vertical and parallel lines so that the chair is not comfortable in use nor pleasing in appearance. It has been desired in chairs of this character to so arrange the parts that the side members will diverge slightly in a forward direction from the back of the chair so that the chair will neither present a rigid, stiff, appearance nor be uncomfortable to use.

An object of the present invention is therefore to provide a chair which may be collapsed and which employs an X-brace construction for this purpose which is so designed that the side members will diverge from each other from the back of the chair forwardly and which will not only be sturdy in construction but may be collapsed readily with a minimum amount of effort and without binding.

Another object of the invention is to provide a collapsible chair with a novel connection between the sides of the seat-forming element or elements and the seat rails of the chair enabling the seat-forming elements to be readily removed from time to time as occasion may require for laundering or cleaning purposes, and to be subsequently replaced. The ability to remove and replace the seat-forming element or elements also enables a number of chair frames to be kept in stock and have supplied thereto a seat cover which may be colored or printed to meet the desires of the purchaser.

Another object of the invention is to provide a chair having a flexible backrest which can be easily detached from the chair, cleaned, and replaced, or which may have backrests of other colors or designs readily substituted therefor.

A further object of the invention is to provide a wheel chair having a footrest on the underside of which there is a pedestal arranged to be lo-

2

cated immediately above the supporting surface so that when weight is placed on the footrest in getting into or out of the chair any tendency of the chair to tilt due to the weight on the footrest or to roll away is immediately arrested by the pedestal engaging the supporting surface. In this respect the invention is an improvement over wheel chairs now in general use wherein the footrest is usually spaced a considerable distance above the supporting surface with the result that when the occupant of the chair places his weight on the footrest the chair has a tendency to tilt which has frequently resulted in injury.

Another object of the invention is to provide a wheel chair wherein the wheels are mounted on side rails that are detachably connected to the side members of the chair, the arrangement being such that the side rails are interchangeable. Usually, wheel chairs are equipped on each side with a large wheel that may function as a driving wheel and also a small wheel or caster wheel. Under certain conditions it is desired to have the large wheel near the front of the chair and under other conditions it is desired to have the large wheel near the rear of the chair. By having the side rails on which the wheels are mounted detachable from the chair and interchangeable the chair may be converted so as to position the large wheels at the front or back of the chair as desired.

With the foregoing and other objects in view, which will be made manifest in the following detailed description and specifically pointed out in the appended claims, reference is had to the accompanying drawings for an illustrative embodiment of the invention, wherein:

Fig. 1 is a perspective view of a collapsible stationary type chair embodying the present invention;

Fig. 2 is a front view in elevation of the same;

Fig. 3 is a view in side elevation of the same;

Fig. 4 is a front view in elevation of the chair shown in Fig. 1, illustrating the chair in collapsed position;

Fig. 5 is a partial view in horizontal section and may be regarded as having been taken substantially on the line 5—5 upon Fig. 3;

Fig. 6 is a partial view in elevation and may be regarded as having been taken upon the line 6—6 upon Fig. 5;

Fig. 7 is a partial view in elevation illustrating the details of construction of the latch which may be employed in the construction of the chair;

Fig. 8 is a partial view in elevation of the rear end of one of the seat rails;

Fig. 9 is a partial view in vertical section illustrating the details of construction of one form of connection between the flexible seat elements and the side rails;

Fig. 10 is a view similar to Fig. 9, but illustrating an alternative form of construction;

Fig. 11 is a view in side elevation of wheel chair embodying the present invention;

Fig. 12 is a view in front elevation of the same;

Fig. 13 is a view similar to Fig. 11, but illustrating the side rails as having been interchanged; and

Fig. 14 is a sectional view taken substantially upon the line 14—14 upon Fig. 13.

Referring to the accompanying drawings wherein similar reference characters designate similar parts throughout, the improved chair as illustrated in Figs. 1 to 8, inclusive, comprises a pair of spaced side members, generally indicated at 10 and 11 which may be fabricated of any suitable material, such as for example plywood. These side members provide front legs 12, rear legs 13, bottom rungs 14, seat rungs 15, and arm rests 16.

The X-brace construction, generally indicated at 17, connects the two side members to each other. The X-brace construction illustrated consists of two X-braces, each composed of legs 18 and 19 pivotally connected together adjacent their centers by a connecting rod 20. The lower ends of these legs are connected to the bottom rungs 14 of the side members as by hinges 21. The upper ends of these legs are connected to seat rails 22 and 23. These seat rails are rigid with the upper ends of the legs of the X-brace.

A feature of the construction resides in the arrangement of parts so that the side members 10 and 11 may diverge forwardly instead of being perfectly parallel to each other as in the conventional collapsible chair of this type. To this end, as will be observed from Fig. 3, the planes of the X-braces are inclined upwardly and rearwardly instead of being arranged vertically and preferably the bottom rungs 14 are inclined downwardly and rearwardly instead of being horizontal so that the hinge members 21 may be located at approximately midway between the top and bottom of the bottom rungs. With this arrangement, the seat rails 22 and 23 may be so mounted on the upper ends of the X-brace construction as to diverge forwardly with approximately the same degree of divergence as the side members 10 and 11.

In the conventional chair of this type the seat rails have some sort of slidable connection with the front legs of the side members. However, in the present construction I find it advisable to omit such a slidable connection in order to avert any tendency to bind. On the inner faces of the rear legs 13 only I provide guide bars or rods 24 and secure apertured plates 25 to the seat rails at their rear ends. The guide rods or bars 24 loosely extend through the apertures in these plates and are anchored at their top and bottom to the legs 13. Intermediate the top and bottom these guide bars or rods are spaced slightly from the inner faces of the legs 13. By this form of construction it will be appreciated that the side members 10 and 11 must diverge forwardly and if desired the seat rails may be tilted downwardly and rearwardly toward the back, thus producing a collapsible chair of this type which is comfortable in use and pleasing in appearance. When the side members 10 and 11 are moved

towards each other the legs 18 and 19 of the X-brace construction pivot relative to each other with the apertured plates 25 merely sliding up on the guide bars or rods 24. Outward movement of the side members 10 and 11 may be limited by a flexible, but inextensible member 26 connected to the opposed seat rungs 15. When the outward movement of the side members is arrested further pivotal movement between the legs 18 and 19 is arrested thus limiting the position of the seat rails 22 and 23. The front legs 12 may have pivoted latches 27 mounted thereon which are receivable in ferrules 28 recessed in the forward ends of the seat rails 22 and 23. These latches may be swung into engaging position and when engaged will prevent movement of the seat rails relative to the side members 10 and 11. Whenever the latches are disengaged the chair may be collapsed as above described.

A feature of the construction is the manner of attachment of the seat-forming element or elements to the side rails. As illustrated in Figs. 9 and 10, the top edges of the side rails are grooved as at 29 and a metal cover strip 30 is fastened to the seat rails between the grooves and extends partially thereover so that the interiors of the grooves are larger than the entrances thereto provided by the edges of the strip 30 and the top surface of the seat rail. The flexible seat that connects the seat rails may consist merely of a section of fabric, such as canvas 32 which is reversely folded at its sides around a length of rope 33. The reversely folded portion may be stitched to the body of the fabric to inclose the rope. This rope or the equivalent provides longitudinally extending enlargements at the side edges of the fabric which can be slid lengthwise into the innermost grooves 29. Inasmuch as the entrances to these grooves are narrower than their interiors and the enlargements practically fill the interiors of the grooves they cannot be withdrawn from the grooves. In this manner, the seat will be uniformly held throughout the length of each of its side edges, so that the fabric will not become stretched or unduly stressed in certain localities as is frequently the case where a series of spaced independent fasteners are employed to attach the fabric seat to the seat rails. If desired, one side of the fabric may have an additional rope or cord secured to its underside parallel to the rope 33 and this additional rope may be slipped into the groove in lieu of the rope 33 to take up slack in the event that the fabric stretches and sags.

The above-described construction embodies the fabric seat element which may be withdrawn or removed from the chair for cleaning purposes or for substitution. This may be accomplished by merely sliding the enlargements provided for by the ropes 33 forwardly through the grooves until they are completely withdrawn.

In some forms of construction I employ in addition to the seat element 32 a seat cover 34 which is similarly constructed having enlargements provided by ropes 35 at its side edges which are receivable in the outermost grooves 29 and when such a seat cover is employed it may be desirable to interpose between the cover 34 and the element 32 a cushion 36. The cover may similarly be removed from the chair for purposes of cleaning or if desired, it may be substituted with another cover of different color or design. The cover may be equipped with a skirt 37 at its forward edge

which hangs downwardly a suitable distance from the forward edge of the seat.

In Fig. 10, I have illustrated an alternative form of seat construction wherein the seat element 38 has enlargements 39 receivable in the groove 29 and the cover 40 is formed of upper and lower fabric sections between which there may be filling or padding 41 forming a cushion. These fabric sections may be integral with each other and encircle a rope 42 providing enlargements at its side edges which are receivable in the outermost grooves 28.

As illustrated in Fig. 5, the opposed faces of the rear legs 13 may have grooves 43 formed therein which have narrow entrances and a flexible backrest 44 connects the upper portions of these rear legs. The backrest is similarly reversely folded about an enlargement forming rope 45 which can be slid into the tops of the grooves 43. When so mounted the backrest cannot be withdrawn from within the grooves except by sliding it vertically out of the grooves whenever cleaning or replacement is required.

In Figs. 11 to 14, inclusive, I have illustrated the invention as having been incorporated in a wheel chair wherein the body of the chair, generally indicated at 50, is of the same construction previously described. In addition thereto, there are provided a pair of side rails 51 which are detachably connected to the front and rear legs of the side members such as by bolts and wing nuts 52. The rear ends of these side rails may be equipped with caster wheels 53 and adjacent their forward ends they may be provided with axles or bearings for large drive wheels 54. The side rails are provided with a series of bolt holes 55, any of which may receive the bolts and wing nuts 52. Thus, if it is desired to convert the wheel chair so that the drive wheel 54 instead of being located near the front of the chair, is located near the back of the chair it is merely necessary to remove the side rails and their attached wheels and apply them to the opposite side of the chair (compare Figs. 11 and 13). The side rails are equipped with a pair of links 56 and 57 which are connected thereto, such as by bolts and wing nuts 58. These bolts and wing nuts when loosened will permit of adjustment of these links from the full line position shown in Fig. 11 to the dotted line position shown therein. The links have secured to their lower ends a footrest 59 and on the underside of this footrest there is mounted a pedestal 60, the bottom of which is only a short distance above the supporting surface. When the occupant of the chair in getting in or out of the chair places considerable weight on the footrest which would otherwise tend to tilt it about the foremost wheels, this pedestal quickly engages the supporting surface and arrests such tilting movement. It will be understood that when the footrest 59 is in any adjusted position that it is rigidly maintained therein by the tightening of the wing nuts 58. A flexible panel 61 may be connected between the side members of the chair and may be connected to the footrest and when the footrest is swung into an upper position indicated by dotted lines on Fig. 11, this panel may serve to support the legs of the occupant. In this form of construction the flexible backrest, instead of being mounted between the upper ends of the rear legs 13 may be mounted between arms 62 which are pivotally mounted on the rear legs 13 as at 63. These arms may be swung rearwardly into any adjusted position and then tightened or held in such position by tightening bolts and wing nuts

64 on the arms which traverse a slotted quadrant 65. It will be appreciated that when the side rails 51 and their associated structure are applied to the chair that the chair is held against collapse by the footrest 59. However, on detaching the footrest from the side rails the presence of the side rails and associated structure does not interfere with the normal collapse of the chair facilitating its being collapsed whenever it is desired to store or transport the same.

From the above-described construction it will be appreciated that an improved chair is provided which may be either of the stationary or wheel type and which is of novel construction in that the side members need not be parallel but may diverge forwardly lending to the chair an inviting and comfortable appearance. Furthermore, the improved chair may be converted from a stationary chair into a wheel chair or vice versa by the application or removal of the side rails and their associated structure. The drive wheels 54 may be located near the front of the chair or near the rear of the chair depending upon which side of the chair the side rails are attached to. By employing various holes 55 for the reception of the bolts and wing nuts 52, the position of the drive wheels 54 may also be varied.

It is to be understood that when the word rope is used in the claims that it is intended to cover ordinary types of rope, and also cloth, twine or thread which is formed into a rope like shape.

Various changes may be made in the details of construction without departing from the spirit and scope of the invention as defined by the appended claims.

I claim:

1. In a collapsible chair, a pair of seat rails each having a pair of longitudinally extending grooves therein, the interiors of said grooves being larger than their entrances, a flexible element having longitudinally extending enlargements along its side edges receivable in the innermost grooves only in the seat rails, a seat cover having longitudinally extending enlargements along its side edges receivable in the outermost grooves only in the seat rails, and a cushion between the flexible element and the seat cover, the enlargements of the flexible element and the seat cover being formed by enclosing lengths of rope.
2. In a collapsible chair, a pair of seat rails each having a pair of longitudinally extending semi-circular grooves therein, a single closing strip secured to each rail and disposed between the grooves of each rail and having portions overhanging the grooves to restrict the entrances to the grooves, a flexible element having longitudinally extending enlargements along its side edges receivable in the innermost grooves only of the seat rails, a seat cover having longitudinally extending enlargements along its side edges receivable in the outermost grooves only in the seat rails, and a cushion between the flexible element and the seat cover, the enlargements of the flexible element and the seat cover being formed by encircling lengths of rope.
3. In a collapsible chair, a pair of seat rails each having a pair of longitudinally extending semi-circular grooves therein, a single closing strip secured to each rail and disposed between the grooves of each rail and having portions overhanging the grooves to restrict the entrances to the grooves, upper and lower fabric sections formed integral with one another to present an endless belt, a pair of lengths of rope encircled

and retained by the upper and lower fabric sections to provide opposed longitudinally extending enlargements receivable in the outermost grooves only in the seat rails, and a bottom fabric section between the seat rails, two opposed margins of the bottom section each encircling a length of rope and being fastened to the main body of the bottom section to provide longitudinally extending enlargements receivable in the innermost grooves only in the seat rails.
